HIGH FREQUENCY RADIO APPARATUS

William W. Hansen, Russell H. Varian, and John R. Woodyard, Stanford University, Calif., assignors to The Board of Trustees of The Leland Stanford Junior University, Stanford University, Calif.

Application April 20, 1939, Serial No. 268,898

14 Claims. (CL 250—36)

This invention relates, generally, to the generation and utilization of ultra high frequency currents and the invention has reference, more particularly, to novel high frequency radio apparatus including electronic oscillators or converters of the general type disclosed in copending application Ser. No. 168,355, now Patent 2,242,275 filed Oct 11, 1937, of which Russell H. Varian, one of the joint applicants hereof, is the inventor.

The electrical converter of this prior application consisted essentially of two spaced hollow conducting circuit members within which fields comprising standing electromagnetic waves are adapted to be set up by the passage of a stream of electrons therethrough, the said members being so constructed, as by having reentrant apertured portions or poles through which the electron stream passes, that electrons pass completely through the field of each member preferably within the period of a half cycle or less of the operating resonant frequency of the conducting members. With the electric vector of the electromagnetic field of each member acting along the line of travel of the electrons and upon the latter for a time preferably equal to one half cycle or less, successive electrons of the beam will emerge from the initial hollow resonant member with variable velocities and will move through the space separating the two members, whereby a concentration of electrons will form around electrons of normal velocity that are preceded by slow electrons and followed by fast electrons. Likewise, diminished numbers of electrons will obtain around electrons of normal velocity that are preceded by fast electrons and followed by slow electrons. Thus, the electrons of the beam pass a given point in waves of increasing and decreasing density, which waves are caused to pass through the second hollow resonant member, having substantially the same resonant frequency as that of the initial member, whereby electromagnetic waves are excited in the second member that are stronger than those existing in the initial member. With proper coupling of the electromagnetic waves in the second member with those of the initial member sustained electromagnetic oscillations will result, such coupling obtaining when the electron groups pass the mid-point between the reentrant portions or poles of the second or energy absorbing resonant member when the field in that member is most strongly opposing the motions of the electrons therethrough. Since the electron group gathers around the electrons of normal velocity which are preceded by slow electrons and

followed by fast electrons, this group of normal velocity electrons should pass the mid-point in the field of the initial resonator when that field is zero and changing so that the following electrons will be assisted thereby. Thus, it follows that the phase of arrival of the electron groups at the mid-point of the field in the energy absorbing or second resonant member preferably should be $\frac{3}{4}$ of a cycle later than the phase of arrival of the groups at the mid-point of the energy grouping circuit or initial resonator.

If no coupling is provided between the resonant members, the device will act as an amplifier of electromagnetic waves at the resonant frequency of the system. Inasmuch as energy is extracted from the electrons on an average by the second resonant circuit member, i. e. while the majority of electrons moving therethrough lose energy therein, there are always some electrons receiving an increase in energy so that it follows that with no oscillations in the second resonant circuit member the electrons of the beam after emerging therefrom will all have substantially the same kinetic energy as initially, but when oscillations occur therein some electrons will have greater energy and some less. Therefore, any device which segregates the electrons of the beam into groups dependent upon their energy or velocity will serve to detect the presence of oscillations in the second resonant circuit member.

The principal object of the present invention is to provide novel high frequency radio apparatus of high efficiency and including an electronic oscillator of the general type disclosed in the above mentioned application but which is so constructed and arranged that the same may be successfully operated without the use of tuning and coupling controls, the oscillator of this invention, at least in some instances employing, in effect, but a single resonant circuit in lieu of the two independent circuits of the device of the above application.

Another object of the present invention lies in the provision of novel forms of internally resonant hollow conducting members arranged to react with the electron streams passing therethrough to produce oscillators that are adaptable for use as oscillator detectors.

Another object of the invention is to provide an oscillator having two resonant chambers together with novel improved means for tuning one chamber with respect to the other.

Still another object of the present invention is to provide an oscillator of the electron beam type

wherein grids are eliminated so that electrons are not lost by collision with grids.

A further object is to provide a single resonant conducting oscillator of large power output, one type of such oscillator having a radially extending electron beam.

A further object is to provide novel means for modulating an oscillator of the velocity grouped electron beam type employing but a single resonator.

Another object of the invention is to provide efficient electronic oscillators utilizing a single resonant hollow conducting member employing a velocity grouped electron beam and in which the efficiency of operation of the apparatus is not a critical function of the relative dimensions of the parts of the conducting member.

A still further object is to provide a high frequency apparatus having a grid that is so constructed and arranged that the same acts differently upon electrons passing through differing portions of its cross section.

Still another object is to provide a novel grid construction having a high heat conductivity and a low intercepting effect not only as applied to a beam of electrons having parallel moving electrons but also when applied to a beam having electrons diverging radially with respect to the axis of the grid.

A further object is to provide a resonant hollow conducting member providing two regions therein adjacent a bounding surface, in one of which regions electrons are subject to a relatively weak action by the contained field and in the other region the electrons are subject to a relatively strong action by the contained field.

A further object is to provide an oscillator of improved efficiency wherein electrons are projected through and outwardly of an internally resonant hollow conducting member and are then reflected back into said member again.

Another object is to provide a novel high frequency oscillator that is adapted to be readily assembled and disassembled and suitable for use in connection with a vacuum pump.

Other objects and advantages will become apparent from the specification, taken in connection with the accompanying drawings wherein the invention is embodied in concrete form.

In the drawings:

Fig. 1 is a schematic view in section of a pair of resonators for use in explaining the theory of operation.

Fig. 1A is a schematic view in section of a single member embodying both resonators of Fig. 1.

Fig. 1B is a schematic view in section of a modified construction.

Fig. 2 is a sectional view of a practical form of oscillator, the parts of which are adapted to be readily assembled and disassembled, the apparatus being shown for use in connection with a vacuum pump.

Fig. 3 is a schematic view in section of a form of resonator.

Fig. 3A is a schematic view in section of a modified form of the structure shown in Fig. 3.

Fig. 4 is a central sectional view of a radio receiver embodying principles of the present invention.

Fig. 5 is a schematic view in section illustrating a somewhat modified form of resonator.

Fig. 6 is a view similar to Fig. 5 but illustrates a modified construction.

Fig. 7 is a central sectional view of apparatus embodying an annular type oscillator adapted for large power output.

Fig. 8 illustrates a form of the apparatus 5 wherein a cathode ray beam having a variable focus is used for exciting the resonant circuit, this figure also showing means for concentrating the beam so as to use but a single hole instead of a grid structure in the resonator. Fig. 8A is a modified detail.

Fig. 9 is a central sectional view of an oscillator having a single resonant circuit and embodies certain principles of the present invention.

Fig. 10 is a view similar to Fig. 9 but illustrates 15 a different construction.

Fig. 15 is a sectional view of a power oscillator employing the principles of Fig. 13 but wherein the beam extends radially.

Fig. 16 is a sectional view of a receiver utilizing the type of resonator shown substantially in 30 Fig. 1A.

Fig. 16A shows a modified detail.

Similar characters of reference are used in all of the above figures to indicate corresponding parts.

35 In the oscillator of the above mentioned prior application two resonant circuits are employed together with coupling means interconnecting the two. While it is possible to determine, with reasonable accuracy, the ratio of voltages desired

40 between the grids of the respective resonant circuits so that thereby one might determine the proper proportions and dimensions of the resonant circuits and so be able to do without various adjustments such as tuning the circuits individually and altering the coupling therebetween, yet it is found in practice that even when so properly calculated and adjusted to operate under certain circumstances that these adjustments must be changed slightly in the course of time due to

45 the slight changes in dimension, etc. This would be expected because the maintenance of some fixed voltage ratios involves the two tuned circuits staying in exact resonance and this is unlikely because of the extreme sharpness of the resonance.

50 In certain devices of the present invention the two tuned and coupled circuits of the prior patent are combined in effect into a single circuit so constructed and arranged as to operate in the manner of a Klystron oscillator i. e. a converter composed of two resonant circuits excited and coupled by a beam of electrons projected through the fields of the resonant circuits, as disclosed in application Serial No. 168,355, now Patent 2,242,275, and which needs no tuning or coupling controls.

55 Referring now to Fig. 1 there is shown an upper resonator 1 and a lower resonator 2 separated therefrom. These resonators are illustrated as excited by oscillators 3 and 4 respectively, through use of coupling loops 3' and 4' extending into the interiors of the resonators so as to set up and link the standing electromagnetic fields therein. Although resonators 1 and 2 are shown as of differing lengths they may be

made to have the same resonant frequency by proper proportioning of the lengths thereof with respect to the width of the gaps 5 and 5'. These gaps are produced between reentrant end portions 6 and 6' and the opposite ends of the resonant containers. If it be assumed that members 1 and 2 are calculated so as to have the same frequency and that the strength of excitation thereof by means of loops 3' and 4' are so adjusted that the magnetic fields at the two coupling loops are equal, then, the currents in the copper or wall surfaces near the loops are equal in magnitude. Thus, the currents as shown by the arrows are of equal magnitude and of opposite phase so that if the two resonators are combined as shown in Fig. 1A, i. e. the two ring-shaped ends are replaced by a single diaphragm 7 in Fig. 1A, then this ring-shaped section will carry high frequency currents on opposite sides that are substantially equal and opposite and hence it follows that this ring-shaped diaphragm may be removed without altering the field distribution. Such a structure is illustrated in Fig. 1B which may be designed to have the same resonant frequency as either Fig. 1 or Fig. 1A. In this construction shown in Fig. 1B we have in effect an exterior container 8 shown as of cylindrical shape together with an interior hollow cylindrical member 9 that is concentric with the member 8. Member 9 is shown supported by vertical struts 10 and 10'. Also, it will be noted that the total potential drop in the field across gap 5 of Fig. 1B is less than the total potential drop across the field of gap 5' of this figure just as in the preceding figures. The ratios of the voltages across gaps 5 and 5' may be anything desired, depending, of course, upon the design of the resonator.

It may be that for mechanical, thermal or electrical reasons it is desirable to have supports or conductors leading from the outer container to the inner container as is shown in Fig. 3 and 3A. In these figures the diaphragm is shown replaced by wires 1'. Since the electric field is substantially zero in the region of the wires 1' no distortion of the field will result due to the presence of these wires. It will be noted by referring to Fig. 3 that the gaps 5 and 5' are equal and that the struts or wires 1' are located midway of the height of the outer cylinder 8. Here it is plain by symmetry that in the midplane where wires 1' are located, the electric field is zero and the voltage across gaps 5 and 5' are equal. If now the cylinder 9 is translated upwardly somewhat as shown in Fig. 3A the field will alter its distribution so that the voltage or potential drop of the field across gap 5 becomes less than that across gap 5'. Also the nodal surface of the electric field moves upwardly so that it is necessary to also move the transverse struts 1' upwardly as shown in Fig. 3A. Also the region where B or the magnetic field is a maximum likewise moves upwardly so that for maximum effectiveness coupling loop 23 must also be moved upwardly.

If desired, instead of using a loop to excite the resonators of the preceding figures, they may be excited by a stream of electrons as shown in Fig. 2. In Fig. 2, 11 designates an indirectly heated cathode having a heater 12 supplied from a battery 13 through a vacuum seal 14. The cathode 11 is shown carried by diaphragm 14 mounted on an insulating support 15. Cathode 11 is shown provided with a collimating shield 16 for collimating the electron beam to direct the same through central grids 18, 19 and 20 of the resona-

tor 22. Grid 18 is in the upper end of the exterior container or resonator 22, whereas grids 19 and 20 are in the ends of the interior hollow cylindrical member 21. Member 21 is shown fixedly supported within the interior of resonator 22 by the insulating struts 10, 10' and conducting wires 1'. The battery 17 connected between the cathode 11 and resonator 22 serves to accelerate the electrons of the cathode ray beam. The electrons of the beam in passing through the alternating field between grids 18 and 19 are caused to acquire periodic changes in velocity just as in the case of the "buncher" in the apparatus of the before mentioned patent. On leaving grid 19, the electrons pass through the hollow interior of member 21 within which the beam is substantially shielded from any action by the field contained within member 22 and exterior of member 21. By the time the electrons reach grid 20 they have become velocity grouped and, in passing through the electromagnetic field existing between this grid and the lower end of the resonant chamber 22, they deliver energy to this field. A small aperture 24 is provided at the center of the lower end of resonator 22 through which a part of the electron beam passes. A permanent magnet 25 is positioned below aperture 24 and its poles are so disposed that the electron beam passes therebetween, thereby deflecting the beam an amount depending upon the velocity of the electrons. When the device begins to oscillate, the electrons passing through the hole 24 will have differing velocities and the magnet 25 will, therefore, cause the beam to spread out into velocity spectrum which is formed upon a suitable fluorescent screen 26 attached to a glass plate 27 at the lower end of the assembly.

The glass plate 27 is shown clamped upon and sealed to the lower section 29 of the vacuum envelope or casing enclosing the oscillator. Seals 28 are shown used for sealing the several sections of the envelope or casing together and to the resonator 22. Section 30 of the casing is adapted to be connected to a suitable vacuum pump. A tube 31 is shown surrounding resonator 22 for cooling water purposes.

Energy may be removed from the oscillator 22 for utilization such as for supplying an antenna through use of a coupling loop 32 and lead 33 passing through the insulating seal 34. It will be noted that the time of transit of the electrons between buncher grids 18-19 and the catcher grid 20 must be so chosen as to give the proper phase relationships so that the electrons will do work on the field within gap 5'. This may be regulated by varying the voltage used to accelerate the electrons. However, both the flight distance and the ratio of bunching voltage to energy absorbing voltage are fixed and it can be shown that with these elements fixed there is one particular gun, voltage that gives maximum efficiency. If desired, however, the transit time may be varied as by putting in an additional electrode inside the central tube or cylinder 21 and employing this electrode to adjust the transit time. A construction utilizing this method of control is shown in Fig. 4.

Referring now to Fig. 4 the invention is illustrated in the form of a receiver which is contained within an evacuated envelope such as glass that is adapted to be permanently sealed off. Parts of Fig. 4, which are similar to corresponding parts of Fig. 2, are similarly numbered in the drawing. The resonator 35, similar to the

form shown in Fig. 2, is shown contained within the glass member 36 and has the hollow cylindrical member 37 supported therewithin through the use of struts 7'. One strut designated 7" is made hollow and contains a lead 37' which is connected at one end to a potentiometer 38 connected across battery 17 and at its other end this lead is connected to an open ended hollow cylindrical electrode 39 contained within the member 37 though insulated therefrom as by use of the end insulating washers shown. Thus, as the potential on electrode 39 is varied by varying the potentiometer connection of lead 37', the flight time of electrons passing through the hollow member 37 is correspondingly varied, thereby controlling the phase of entry of the electron groups into space 5' as desired. Since the electrode 39 determines the phase of the electron bunches arriving at the catcher end or space 5' this electrode may be used to determine the strength of the oscillations in the resonator and may be used for turning the oscillations on or off should the device be used as a super-regenerative receiver. Incidentally the electrode 39 may be used for modulation purposes in the event the apparatus is used as a transmitter in the same manner as described in connection with application Ser. No. 218,064, filed July 8, 1938, Electronic oscillator detector, William W. Hansen, Sigurd H. Varian and Russell H. Varian.

In order to control the frequency of resonator 35 at will, the member 36 is shown provided with a reentrant tubular projection 40 that extends into the interior of the resonator 35. The interior of this tubular projection is open to the atmosphere and contains a block 41 of preferably electrically conducting material which is adjusted longitudinally of projection 40 by use of a metal rod 42 fixed on member 41 and extending outwardly of tube 40 for receiving a nut 43 confined within a guide block 44 that is attached to the projection 40. Thus by turning nut 43 the block 41 is moved longitudinally of projection 40 within resonator 35, thereby varying the resonator frequency thereof and enabling the ready tuning of this device. By use of this device it is unnecessary to seal the joint between the rod 42 and the envelope. This tuning device may be used in any of the structures of the invention. The device of Fig. 4 is shown provided with a detector arrangement that is somewhat similar to the form shown in application Ser. No. 218,064, above mentioned. In Fig. 4 two spaced grids 45 and 46 are positioned below the lower resonator grid 47. The grids 45 and 46 are shown as having a form somewhat similar to a gable roof construction, the two sloping sides of the grid slanting but slightly from the horizontal, this slant being only sufficient to divert reflected electrons away from grid 47. Plate 48 is placed below the grid 46 and is connected to the intermediate frequency amplifier 49 which in turn is connected to the audio detector 50, which in turn is connected to the phones 51. Grid 45 is at anode voltage and grid 46 is connected through lead 51' to potentiometer 52 connected across battery 53 having a tap extending to the cathode 11. Thus, the potential of grid 46 may be adjusted so as to reflect slow electrons while permitting fast electrons to go therethrough thereby obtaining detection. The high frequency signal is received by lead 33 and loop 32, this signal being of slightly different frequency from that of the oscillator of Fig. 4, the resultant of which when detected by the combination of grids 45 and 46

and plate 48 is a difference beat frequency and is supplied to the intermediate frequency amplifier 49, the output of which is detected by the audio detector 50 for supplying the phones 51.

Fig. 5 shows a somewhat modified form of resonator 53. In this form of resonator the side walls are shown substantially curved, somewhat in the manner of an ellipse, whereas the inner cylinder member 9' has concaved outer walls. This form is somewhat more efficient than the previous forms of resonators shown. Obviously other shapes may be used if desired. The types of resonators heretofore described have but one nodal plane of electric field and are of a length of a quarter wave length or less. There is no reason, however, why resonators cannot be used having two nodes of electric field and such a resonator is shown in Fig. 6 and designated 55. In this resonator the conducting struts 56 and 56' supporting the inner cylindrical member 58 are located at the nodal planes and it will be noted that the loop 57 illustrated for maintaining the standing electromagnetic field is arranged symmetrically with respect to the struts 56'. As compared with the preceding figures this form of the invention has a somewhat lower shunt impedance and is probably stronger mechanically since two sets of supporting struts 56 and 56' are used. Of course, just as in the case of Figs. 1, 1A, 1B, 3, and 3A and 5 the ends of resonator 55 and those of enclosed member 58 would be suitably provided with grids or openings in the event these resonators are to be excited by an electron stream such as illustrated in Figs. 2 and 4.

In the event that large power output is required a resonator such as the type shown in Fig. 7 may be employed. Here also the resonator 59 is shown contained within an evacuated container 60 in a permanently sealed off condition. It will be noted that the resonator 59 is of an annular shape and is derived from the type of resonator shown in Fig. 2 by revolving the cross section of the resonator of Fig. 2 about an axis eccentric thereto, thereby forming an annular chamber within which the frequency of the standing electromagnetic waves will be substantially the same as that of the member 22 of Fig. 2. The internal cylindrical member 21 of Fig. 2 has also been revolved in Fig. 7 to produce the internal hollow annular member 61. The member 59 is provided with an annular grid 18' while the member 61 is provided with annular grids 19' and 20'. The emitter 11' is also annular in shape. With this construction the electron beam is of annular cross section and is quite large, thereby providing for large power output which may be taken out through the loop 32 which may be used for exciting an antenna. A water cooling coil 62 is shown to provide for cooling the resonator in use. Note that the positive side of battery 17 is connected to the resonator 59 through the cooling pipe 62. The advantage of this type of oscillator, of course, lies in the fact that the frequency is not greatly different from the type shown in Fig. 2 having substantially the same size of generating cross section, whereas the grid area through which the beam is projected is enormously expanded thereby providing large power at short wave lengths.

Referring now to Fig. 8 the electronic oscillator therein shown is of the same type as that described in the preceding figures but this form of the invention employs an electron focused beam of variable focal length as a function of electron

velocity to thereby obtain bunches of electrons for driving purposes. In this figure, a focusing thermionic cathode 63 is used having a heater element 64 supplied from battery 18 through leads 68. Cathode 63 has a concave shield 65 surrounding the same and cooperating therewith to focus an electron beam through a central aperture provided in a hollow truncated projection 73' formed on a hollow anode 73. A solenoid 69 surrounds the resonator 67 and the electron beam for producing a magnetic focusing field which focuses an electron image of the hole 66 between holes 70 and 71 provided respectively in the top of resonator 67 and the top of member 72, as illustrated in Fig. 8. The field of member 69 also focuses a second electron image either in advance of the lower aperture 74 of member 72 or beyond this aperture depending upon the velocities of the electrons. In the space 5 between holes 70 and 71 the electrons receive periodic increases and decreases in velocity which will shift the focal point at hole 74 along the axis of the beam in a manner well known in electron optics. This shift in focal point will alternately focus the electron beam through the hole 74 and blur it out so that most of the electrons miss this hole. This action will cause a pulsating stream of electrons to pass through the hole 74 and to the lower end of the resonant conducting member 67. This pulsating stream of electrons excites standing electromagnetic waves within the interior of member 67 in the same way as the pulsating stream of electrons obtained by ordinary velocity grouping such as in the preceding figures.

It will be noted that the resonator 67 is shown provided with a coupling loop 75 and lead attached thereto for extracting electromagnetic energy from the oscillator for utilization. A nut 76 threaded upon a rod 77 is held against longitudinal movement by a suitable guide frame 87. Rod 77 is shown headed at its upper end which end is connected by quartz rods 78 to the lower end of cylindrical member 72. The upper end of this member is connected through quartz rods 78' to the inner ends of leaf springs 79 having their outer ends fixedly attached to resonator 67. By turning nut 76, rod 77 is moved longitudinally, thereby moving cylindrical member 72 vertically within resonator 67, such movement acting to vary the ratio of the electron velocity change occurring between holes 70 and 71 to that occurring between hole 74 and the lower end of the resonant chamber 67 while leaving the resonant frequency substantially unchanged. The use of this adjustment renders it unnecessary to calculate exactly what the spacing at the two ends of member 72 should be to give maximum efficiency. A section of flexible walled tubing 80 surrounds a portion of rod 77 to maintain the vacuum within chamber 67.

Means is also shown in Fig. 8 for varying the frequency of oscillation of member 67 at will by flexing the lower end 81 thereof. This is accomplished through use of a nut 82 confined by guide frame 87 and threaded upon a sleeve 84 connected through push rods 83 to the flexible bottom 81 of the resonator 67. By turning nut 82 the same acts through sleeve 84 and rods 83 to move the diaphragm 81 vertically thereby flexing this diaphragm and correspondingly changing the frequency of oscillation of member 67. A cooling coil is shown at 86.

Fig. 8, taken in conjunction with Fig. 8A, may be used to illustrate another structure involving

another mode of operation of a velocity grouped oscillator. The velocity grouped oscillators heretofore illustrated employed a rather broad pencil of electrons which are projected through closed resonators and through grid structures forming a part of the walls of such resonators. This type of construction while yielding satisfactory results, nevertheless wastes the energy of those electrons that collide with the meshes of the grids.

10. By focusing the electron beam through single holes, as shown in Figs. 8 and 8A, no such loss occurs, but in order for Fig. 8 to function efficiently as a velocity grouped electronic oscillator the hole 74 must be made of such size that substantially all the electrons of the beam pass therethrough as shown at 74' in Fig. 8A. This condition may be met in either of two ways or by a combination of both. Either hole 74 may be left unchanged in size and the angular divergence of

20. the beam as it passes through a focus reduced or the angular divergence of the beam may be left the same as in Fig. 8 and the size of the hole 74 enlarged, as shown at 74' in Fig. 8A. In either case, the distance that the focus of the electron beam may move along the axis thereof without having electrons strike the edges of the hole 74 or 74', as the case may be, is increased. If the electrons do not strike the edges of holes 74 and 74' the electrons will be velocity grouped as previously explained in connection with Fig. 2 and will deliver energy into the interspace 5' between hole 74 and bottom 81. Actually hole 74' may be made quite large without impairing the operation of the device. In fact it may be made any desired dimension up to a diameter of about one third of the distance that an electron travels in one cycle.

30. The form of the invention shown in Fig. 10 illustrates still another type of velocity grouped electron beam oscillator. In this type of oscillator the dimensions of the same can be varied within relatively wide limits without impairing the operation thereof. In this respect this type of oscillator has advantage over the forms shown in Figs. 2, 4 and 8 wherein the position of the metal struts 7' must be more or less accurately placed in order to obtain satisfactory operation.

40. Although the structure of Fig. 10 has a superficial structural resemblance to that illustrated in Fig. 2, for example, yet the mode of operation of the structure of Fig. 10 is quite different. In Fig. 2 the structure is produced by initially starting with two resonators as shown in Fig. 1 that have the same frequency but different a-c voltage across the gaps 5 and 5' through which the electrons pass. These two resonators illustrated in Fig. 1 are turned into one by removal of most of the intervening partition 7 shown in Fig. 1A, the remaining metal supports 7' being located at the voltage node.

50. On the other hand the resonator of Fig. 10 is inherently a single resonator broadly of the concentric line type and is so constructed that the electric field component in the velocity grouping region therein is weaker than that in the energy absorbing region. This is accomplished by projecting the electrons into the device at a point where the field is relatively weak and then projecting them out again where the field is strong.

60. In this figure, 88 is the outer resonant hollow conducting member and 89 is the inner hollow conducting member of a concentric line. Member 89 is provided with upper tubular trunnions or supports 90 and 90' which are secured at their outer ends to the inner wall of member 88.

70. 75.

Since 88 and 89 constitute a concentric line, the device would operate equally well with one of the trunnions 90 or 90' omitted. This structure differs from an ordinary concentric line in that the portion 90 or 90' thereof constitutes a right angled bend in the inner line member 89. Ordinarily, this member would extend upwardly and join the upper end closure of the outer conducting member 88 but this is not done in this structure in order to avoid the necessity of turning the electron beam through a right angle, because it is difficult to make an electron beam turn a corner, it being easier to put a corner in the inner member of the concentric line.

An emitter 11 is provided as in the preceding figures and the electrons therefrom pass in a stream downwardly through a grid 91 in the upper end closure of member 88. This stream also passes through grids 92 and 93 provided in the ends of inner member 89. When oscillations are set up between members 88 and 89, due to the passage of the electron stream, a relatively weak electric field is set up between grids 91 and 92, whereas a relatively strong electric field is set up between grids 93 and the lower end closure of member 88. The relatively weak field between grids 91 and 92 is well suited to perform the function of a velocity grouping field, whereas the relatively strong field below grid 93 serves well as an energy absorbing field. Loop 94 is shown for removing power from the oscillator. It should be pointed out that the reason the electric field is relatively weak between grid 91 and grid 92 is because grid 91 is near the point where the inner conducting member joins the outer conducting member, and, as is well known, the electric field in this region is weak.

Still another type of velocity grouped oscillator is shown in Fig. 9. In this figure the hollow resonator 95 is provided with an upper grid 96 and a second grid 97 located near the bottom thereof and carried by horns or trunnions 99 and 99', having their outer ends attached to the inner wall of member 95. With a standing field set up within member 95, due to the passage of the electron stream from emitter 11 through grids 96 and 97, it will be found that a relatively strong field is obtained between grid 97 and the lower end of member 95, whereas a relatively weak field extends between grids 96 and 97. The field between these grids is well suited for producing the necessary changes in electron velocity to cause velocity grouping of the electrons by the time they enter the space between grid 97 and the bottom of member 95. The electrons traversing the distance between grids 96 and 97 will spend more than one half cycle of the oscillating frequency of the resonator and hence the field in this space will do both positive and negative work on the same electrons. The electrons will, therefore, reach grid 97 with considerably smaller changes in velocity than the change they suffer in going from grid 97 to the lower end of member 95, which latter distance is traversed in preferably less than one half cycle of the resonant frequency of the device. Thus, the conditions necessary for efficient operation are obtained, i. e. the energy change suffered by the electrons as a result of the velocity grouping obtained is considerably less than the energy change suffered thereby in the energy extracting field between grid 97 and member 95.

Fig. 11 illustrates a type of oscillator also employing the concentric line construction and wherein velocity grouping of the electrons is ob-

tained and thereafter energy is extracted from the electrons just as in the previous structures. Only a single hollow resonator is used in this figure and comprises a substantially closed hollow cylinder 100 having its longitudinal axis extending at right angles to the axis of electron beam 101. This beam is shown emitted from a converging or focusing type electron emitter 102 contained within an evacuated enclosure 103. A hollow cylinder 104, having its longitudinal axis concentric with the beam axis, connects container 103 with the evacuated cylinder 100 and has a grid 105 at its upper end through which the electron beam passes. A hollow cylindrical member 106 is contained within member 100 and has its longitudinal axis concentric with that of the beam and is supported from one end of the member 100 by a cylindrical post 107. The lower end of cylinder 106 is provided with a grid 108, whereas its upper end is open and faces the open lower end of connecting yoke cylinder 104.

Resonant oscillations are set up in member 100 by the passage of the electron beam and these oscillations are similar to those existing in a concentric line resonator so that member 106 becomes alternately positive and negative at the resonant frequency of the device. The electron beam 101 after passing downwardly through grid 105 passes through a focus substantially in the region between cylinders 104 and 106. Thereafter, this beam again diverges and passes through the grid 108 to the lower wall of member 100. During the passage of the electrons between cylinders 104 and 106, the electrons have their velocities changed by the electric field existing therebetween. However, since the field extends some distance into the open ends of tubes 104 and 106, the electrons spend more than one half cycle within this field with the result that the energy changes of the electrons are reduced by partial cancellation of the work done on the electrons in the first half cycle, i. e. by negative work done thereon during later periods of time. Hence, the energy change suffered by the electrons between grids 105 and 108 is less than that suffered by the electrons in passing from grid 108 to the wall of member 100, thereby obtaining conditions for an efficient velocity grouped oscillator.

The form of invention shown in Fig. 12 operates in much the same manner as that disclosed in Fig. 11, but in Fig. 12 the cross section of the oscillator of Fig. 11 has been rotated about a line eccentric thereto, just as in the case of Fig. 7 previously described. In this way large powers are obtained. Note the use of a converging annular emitter 102' in Fig. 12. Parts of Fig. 12, that correspond to similar parts of Fig. 11, are similarly numbered but with primes applied thereto. Note that the cylinders 104 and 106 are now of annular shape and designated 104' and 106'. Also member 100 is of annular shape and indicated as 100' while 109' is a loop for extracting energy from the interior of the resonator.

In the form of the invention shown in Figs. 13 and 14, a velocity grouped electric oscillator is also shown. In these figures a focusing type electron emitter 110, having an annular ring of electron emitting material 111, is used. Thus, a focused annular electron beam 115 is produced which is passed through a central aperture 112 provided in the bottom of resonator 113 operating on the reflex principle. This resonator has an upper end 114 provided with a peculiar grid construction 116 shown in plan in Fig. 14. Beam

115 is focused between aperture 112 and grid 116. This grid, as shown in Fig. 4, has a central aperture 117 through which the upwardly moving focused beam passes. Thus, the electric field through which the focused beam passes and extending in the region including apertures 112 and 117 is relatively weak and disturbed over more than a half cycle so that the electrons do not suffer much energy change. After passing through aperture 117 the beam travels upwardly while starting to diverge and is slowed down and stopped by the retarding field created by a plate 118 held at a relatively low potential through its connection by a lead 119 to battery 23. Thus, the electrons lose their upward velocity and then fall back and reenter grid 116, passing between the radially inwardly directed grid members 116', thereby reentering the resonator 113. Because of the concentrated electric field existing between grid members 116' and the bottom of resonator 113, the electrons suffer relatively large changes in energy while passing these grid members and the bottom of resonator 113, thereby serving to excite the resonator. Thus, velocity grouping is obtained in the relatively weak and extensive central field of the resonator and catching or energy absorbing operation takes place in the annular region exterior thereof wherein the electric field is much stronger and shorter. The grid 116 is preferably made of good heat conducting material such as copper.

Fig. 15 illustrates an oscillator employing the same principles of operation as those obtaining in Figs. 13 and 14. The resonator in Fig. 15 is produced by revolving the cross section of the resonator of Fig. 13 about a transverse line, i. e. exterior of and below the bottom of the resonator shown in Fig. 13. Note also that the converging emitter 110' of Fig. 15 is of circular shape in plan so as to direct the converging beam radially outwardly therefrom while focusing the beam between annular aperture 112' and annular aperture 117' of the grid structure 116''. Parts of this figure, which are similar to those of Figs. 13 and 14, are similarly numbered but with primes added. By use of the device of Fig. 15, relatively large power is obtained. The frequency of oscillation is approximately the same as that obtaining in Fig. 13 when the revolved cross section is the same as that of the device of Fig. 13.

In the form of the invention shown in Fig. 16, the structure illustrated is quite similar to that shown in Figs. 1A and 4. Note that the oscillator 120 of this figure employs the diaphragm 121, such as illustrated in Fig. 1A, this diaphragm being located in the electric node of the oscillator. The tight coupling between the wave systems in the two resonant members 122 and 123, making up oscillator 120, is obtained by the use of large coupling loop 124, instead of by removal of the partition between the resonant members or chambers 122 and 123. This has an advantage in that the two resonant circuits can be designed so that they will have the same resonant frequency within narrow limits, and the close coupling loop eliminates the necessity for adjusting the degree of coupling between the resonant circuits, while control of the relative amplitude of oscillation in said circuits is controlled by the tuning means.

It is possible to obtain the correct ratio of field between grid 129 and grid 130 to that between 127 and 128 with some given tuning by making a coupling loop with larger area in one chamber

than in the other as is shown in Fig. 16, or it is equally possible to put an equal area of loop in either chamber, and obtain the correct ratio of velocity grouping to energy absorbing fields by slightly detuning one resonant chamber with respect to the other.

An electric coupling means could be used in lieu of loop 124, such a coupling being shown in the form of a conductor 125 in Fig. 16A, this conductor being insulated from the partition 121 as shown. Preferably, conductor 125 would not be placed close to the tuning structure 126', which is similar to that disclosed in connection with Fig. 4. Note that an additional tuning structure 126' is provided in chamber 123. Note that chamber 123 is shown twice as long as chamber 122 and the space between grids 127 and 128 is made twice as great as the space between grids 129 and 130. By this arrangement higher effective shunt impedance for the velocity grouped electron beam passing through chamber 123 is obtained while preserving the same resonant frequency. It is important to have a high shunt impedance for chamber 123 since the intensity of excitation required to produce velocity grouping in chamber 122 of the electron beam is much lower than the excitation necessary in energy absorbing chamber 123.

The cathode construction in Fig. 16 is somewhat different from those shown in the previous figures. In Fig. 16 the cathode is shown as comprising a metal box 131 having a heating filament 132 therein. 133 is a grid like member at the lower end of the metal box and through which the electrons pass. On the upper side of the wires of grid 133, i. e. the side facing the filament 132, a coating of thermionic active oxide is provided. The other side, i. e. the lower side of grid 133, is uncoated. Grid 133 is thus heated by radiation from filament 132 to a temperature at which thermionic emission takes place. The lines of electric force extending between anode grid 129 and grid 133 converge on the wires of grid 133 from all sides. Hence, electrons emitted from oxide on grid 133 are drawn through the apertures of this grid and then passed through grid 129 as a columnar beam of electrons. Positive ions going the other way will pass directly through grid 133 and impinge on various parts of the interior of metal box 131 and heating filament 132, but substantially none of these positive ions will strike the oxide coated surface of grid 133 so that this oxide surface has an exceptionally long life in use. Fig. 16 is shown hooked up as a receiver in the manner similar to that illustrated in Fig. 4.

Although several resonators of this application are shown as metal containers, it is to be understood that if desired these resonators may be made of vitreous material, such as glass, and provided with electric conducting coatings thereby cutting down gas diffusion.

Although the insertable tuning means 41 of Fig. 4 has been described as a piece of conducting material it is to be understood that any object having a dielectric constant differing from that obtaining in the space within the resonator 35 could be used inasmuch as such an object would alter the field distribution within the resonator.

As many changes could be made in the above construction and many apparently widely different embodiments of this invention could be made without departing from the scope thereof, it is intended that all matter contained in the

above description or shown in the accompanying drawings shall be interpreted as illustrative and not in a limiting sense.

What is claimed is:

1. In high frequency radio apparatus, a hollow electrically conducting body arranged to contain standing electromagnetic waves, means for producing an electron beam and for projecting the same into said body, said beam supplying energy toward maintaining the standing electromagnetic waves therein, said body having means contained therein arranged so that different portions of the interior of said body are adapted to contain electric field portions of differing intensities, the beam being projected initially through an electric field portion of relatively low intensity to effect velocity grouping of the beam and finally through an electric field portion of relatively high intensity to effect energy absorption from the beam.

2. High frequency radio apparatus as defined in claim 1, wherein the means contained within said hollow body comprises a hollow member, the interior of which member provides a substantially field free space that is traversed by the electron beam, the portion of the electromagnetic field passed through by the beam before entering said member having an electric field of relatively low intensity, while the portion of the electromagnetic field passed through by the beam after leaving said member has an electric field of relatively high intensity.

3. High frequency radio apparatus as defined in claim 1, wherein the portions of said body containing said low intensity and high intensity field portions are so proportioned that the flight time of electrons within said electric field portion of relatively low intensity is different from the flight time of electrons within said electric field portion of relatively high intensity, the energy interchange between said beam and said field portions being a function of the field intensity and period spent by electrons of the beam therein.

4. In high frequency apparatus, an electrically conducting container, a hollow member within said container, means for setting up standing electromagnetic waves within said container, said waves surrounding said hollow member, said means operating to produce a nodal electric plane within said container exterior of said hollow member, and supporting means for said hollow member extending along said nodal plane and connected to the wall of said container.

5. In a generator of electromagnetic waves comprising an electromagnetically resonant hollow conducting member arranged to have an electric field therein, means for producing a stream of electrons, means for projecting said stream of electrons through a portion of the electric field of said resonator wherein relatively little energy change is suffered by the electrons of said stream to initiate velocity grouping of electrons, means for shielding said electrons from the field of said resonator for a time interval sufficient to allow velocity grouping to be completed, and means for projecting said velocity grouped electrons through another portion of the electric field of said resonator wherein the electrons suffer large changes of energy to deliver electromagnetic energy to said resonator.

6. In a generator of electromagnetic waves containing an electromagnetically resonant hollow conducting member having an electric field therein, said member having an internal hollow con-

ducting portion, means for producing a stream of electrons and for projecting said stream of electrons across a relatively weak part of the electric field of said internally resonant hollow conducting member into said internal portion to effect velocity grouping of the electrons of said stream, and means for projecting said stream of electrons out of said internal portion and through a relatively strong portion of the electric field of said internally resonant hollow conducting member to effect delivery of electromagnetic energy to the field of said hollow conducting member.

7. In combination, an apertured hollow member having a conducting portion, a second apertured smaller hollow member also having a conducting portion suspended within said first member and spaced therefrom to provide a hollow cavity resonator between the outer surface of said inner member and the inner surface of said outer member, means for providing an oscillating electromagnetic field within said hollow cavity resonator at a resonant frequency thereof comprising, means for producing a beam of electrons, means for projecting said beam through the apertures of said first member, through the space between the inner wall of said first member and said second member, through said second member and outwardly thereof through a second space between said second member and said first member, to thereby set up standing electromagnetic waves between said inner and outer hollow members at the natural frequency of said hollow cavity resonator for cyclically varying the number of electrons emerging from within said inner hollow member into the second space between said inner and outer members, to enhance and maintain the standing waves at the natural frequency of said hollow cavity resonator.

8. In apparatus of the kind described, means for producing a system of standing electromagnetic waves having two concentrated high-frequency electric field portions comprising, a hollow conducting member, a smaller hollow conducting member suspended therein and so disposed within said larger member as to establish two regions of reduced clearances of different sizes between said members, and means for establishing standing electromagnetic waves in the space between said larger and said smaller conducting members whereby two regions of concentrated electric fields are established in said regions of reduced clearances.

9. In apparatus of the kind described, an evacuated hollow conducting member, means for changing the electromagnetic resonant frequency of said member comprising an insulating gas tight tube having a closed end projecting into said member, means for sealing said tube to prevent the admission of air to said member, the other end of said tube being open to the atmosphere, an object movable within said tube, and means for controlling the distance of insertion of said object into said tube and said member, to thereby vary the resonant frequency of said member.

10. In apparatus of the kind described, a hollow body arranged to contain standing electromagnetic waves, a shielding member within said body, a conducting member within said shielding member, a hollow conducting conduit member extending between said body and said shielding member, and an electrical connection extending within said conduit member from without said body for controlling the potential within said shielding member.

11. In combination, an apertured hollow conducting member, a second and smaller apertured hollow conducting member suspended within said first member and spaced therefrom to provide a hollow cavity resonator between the outer surface of said inner member and the inner surface of said outer member adapted to contain standing electromagnetic waves, means for producing a beam of electrons exteriorly of said members, means for projecting said beam through the apertures of said members and through an initial space therebetween and into said inner hollow conducting member, focusing means, said beam being controlled by said focusing means and the standing electromagnetic waves within said initial space acting to cyclically vary the number of electrons of said electron beam that fail to pass from the interior of said inner hollow conducting member into the second space between said inner and said outer hollow conducting members, whereby a cycling varying electron current is produced in said second space for sustaining said standing electromagnetic waves.

12. In apparatus of the kind described, a hollow conducting member, a second smaller hollow conducting member suspended within said first member and spaced therefrom to provide a hollow cavity resonator between the outer surface of said inner member and the inner surface of said outer member adapted to contain standing electromagnetic waves, means for projecting a stream of electrons through both hollow con-

ducting members, means for altering the suspended position of said second hollow conducting member by mechanical force applied from outside said first hollow conducting member, to obtain optimum grouping of the electrons of said stream for different projecting velocities of said electrons.

13. Means for producing a beam of electrons comprising a porous substantially planar conducting member, a thermionically emitting coating on one side of said porous substantially planar conducting member, means for heating said porous substantially planar conducting member, and means for drawing electrons from the said thermionically emitting coating through the pores of said porous substantially planar conducting member to the region at the other side of the same.

14. In a high frequency receiver, a substantially enclosed resonator, means for supplying a high frequency signal to said resonator to be amplified thereby, means for producing an electron beam for exciting said resonator, said beam passing outwardly of said resonator after such excitation, and detecting grid means disposed in the path of said beam after leaving said resonator for reflecting slower electrons to one side, said grid means being slightly peaked at its center corresponding substantially to the center of the electron beam and tapering somewhat therefrom.
